United States Patent Office.

SAMUEL W. ADAMS, OF PROVIDENCE, RHODE ISLAND, ASSIGNOR TO
AMERICAN EYELET COMPANY, OF SAME PLACE.

Letters Patent No. 63,131, dated March 26, 1856; antedated March 12, 1867.

IMPROVEMENT IN MACHINES FOR MAKING EYELETS.

The Schedule referred to in these Letters Patent and making part of the same.

TO ALL WHOM IT MAY CONCERN:

Be it known that I, SAMUEL W. ADAMS, of Providence, in the county of Providence, and State of Rhode Island, have invented certain new and useful Improvements in Machinery for Making Eyelets; and I do hereby declare that the following is a full, clear, and exact description of the same, reference being had to the accompanying drawings, making part of this specification, in which—

Figure 1 is a plan of the improved machine, complete.

Figure 2 is a side elevation of the feeding mechanism detached.

Figure 3 is a sectional view of the compound male-cutter and former, and the spindle K that carries the same.

Figure 4 is a side view of the clipping mechanism hereinafter mentioned, detached from the machine.

Figure 5 is a plan of the parts which carry the compound male cutter and former; the female cutter and forming-die and its clearing punch, together with the mechanism which operates the same.

Figure 6 is a plan of the parts which carry the compound male-cutter and former and the clearer (so called) for clearing the formed eyelet from the punch, together with the mechanism which operates the same.

Figure 7 is a side longitudinal view of the said clearer and its operating mechanism, detached; and

Figure 8 is a front or end view of the said compound male-cutter and former; and the clearer, showing the application of the clearer to the purpose intended.

Similar letters refer to corresponding parts in all the figures.

In the drawings, G is the bed or framework of the machine, of cast iron, formed with two stands G² for the bearings of the main shaft A, two other stands G³ for the bearings of the sliding sleeve I, and a stand or knee, G⁴, for holding the compound cutter and die. The material of this bed is of considerable thickness, and it is constructed in the form shown and described to insure the greater stiffness and consequent precision of operation in the working parts. On the shaft A, between its bearings, are secured the cams which operate the mechanism for the performance of the several functions of the machine. The sliding sleeve I is screwed into a cross-head, N, which is connected to the cams B B by the connections E E on each side. The sliding spindle K, within the said sleeve, is screwed into the cross-head D, and connected to the cam J by the connection M. The compound male-cutter 3, and former 2, and central punch 1, are constructed as shown in fig. 3. The shank f of the cutter is fitted into the end of the sleeve I, from which it derives its motion. The former 2 is surrounded by a spiral spring, S, which exerts a force between the shoulder on the former at e and the shoulder at e, on the interior of the cutter 3, to draw the former into the cutter as within a sheath, until the functions to which it is subordinate are performed. A hollow set-screw, n, is screwed into the cavity in the end of the cutter's shank f, by means of which the protrusion of the former 2 is regulated and controlled. Within the former 2 slides the central punch 1, the shank q of which is formed with a shoulder at r, against which the end of the former 2 bears, and from which it derives its motion. The end of this shank q is fitted in the end of the sliding spindle K, by which it is operated; and the parts being thus constructed and arranged, it will be seen that when the central punch 1 is drawn into the former 2, the spring S will press the end of the former against the end of the set-screw n, which, being set at the proper point, will permit the former 2 to withdraw itself into the cutter 3, so that its forming end will be flush or even with the face of the cutter 3, so that in the formation of an eyelet, the external cutter 3 first advances and cuts from the stock a planchet or disk; the central punch 1 then protrudes from the cutter and carries the planchet into the cavity of the forming-die 5, figs. 1 and 5, to form a cup, and when the cup and the punch have advanced sufficiently into the die to fill the same, the continued movement of the punch has a tendency to draw out or elongate the cup until the metal yields to the force of the punch and the top of the cup is cut out; simultaneously with which the former 2 is made to protrude from the cutter in the manner above mentioned, and turns over the flanch on the end of the cup, and completes the eyelet. The immediate parts for forming an eyelet thus far described do not differ essentially in their character or purpose respectively from the "compound moving instruments" and "stationary instruments," (so designated,) for forming an eyelet, set forth and described in Letters Patent of the United States No. 44,555, granted to Jesse F. Richards, Oct. 4, A. D. 1864, to which reference is to be had. But by means of the improved construction and mode of operating the said instruments, as described, greater perfection in the formation of the eyelet

is obtained in respect to the smoothness of the edge from which the top of the cup is punched, and its capacity to stretch without splitting open when used; and the said improvement is therefore herein claimed. The stock is supplied to the machine in the form of a thin metal strip or ribbon, *k*, (represented in red lines,) which, for the sake of convenience, is wound upon a reel, *C*, on one side of the machine, whence it is drawn at intervals by the feeding mechanism, and, after it is operated upon to form the eyelets, the residue is wound upon a similar reel, *C'*, on the opposite side of the machine, as shown in fig. 1, the reel *C'* being revolved by means of a weight unwinding a cord from a drum on said reel or other suitable contrivance to take up the perforated metal strip as it is delivered from the machine. The feeding mechanism which supplies the stock to the instruments for forming the eyelets is represented in fig. 2, and consists of a pair of sliding clamping-jaws *d d'*, on the block *F*, between which the metal strip passes, and is clamped and carried forward at the proper time to be operated upon by means of the lever *H*, pivoted at *L*, and operated by the cam *P* on the main shaft. This cam is of a form to impart two movements through the medium of the lever *H* to the mechanism, one motion being produced by an enlargement on its cylindrical surface which depresses the opposite end of the lever *H* and the arm *x* of the movable jaw *d'*, which swings at *a*, and by the depression mentioned is made to clamp and confine the metal strip *k* between the two jaws; and the other motion being produced by the side face of the said cam, against which the stud *8*, on the lever's end, is pressed by the force of the spring *l*, and swings the lever on its pivot, and causes the opposite end to slide the clamping-jaws and advance the metal confined therein to the eyelet-forming instruments above mentioned. The metal strip is released preparatory to repeating the advancing movement by means of a rubber washer, *Y*, beneath the arm *X*, which lifts the arm when the depressive force of the cam is removed. The sliding movement of the clamping-jaws is adjusted by means of the thumb-screw *7*, to advance the metal strip the requisite distance each time to form the successive eyelets. In the use of a metal strip of sufficient width to cut out more than one row of planchets, a considerable saving of stock, say about one-sixth part, may be made by punching a second row midway between and to one side of the first punching. But in order to do this it is necessary first to trim-off so much of the width of the strip as will permit the cutter to penetrate the strip at the proper distance from the edge thereof. This may be accomplished by trimming off the requisite width of the perforated portion by means of shears or other well-known means, after the strip comes from the machine. But it may be performed with greater accuracy and precision during the passage of the strip through the machine, by means of the clipping mechanism represented in fig. 4, consisting of a shearing-chisel, *p*, attached to and moving with the cross-head *N* of the sleeve *I*, and a corresponding shearing edge, *s*, fixed in the stand *G'*, between which the metal strip passes after being perforated, and is clipped at the proper distance from the edge, (as shown in red lines,) the refuse portion so clipped off being permitted to fall at random beside the machine, while the remaining portion is wound upon the take-up reel *C'*, which, when filled, is shifted to the position of the other reel *C*, for the stock to be again drawn therefrom in punching a subsequent row of planchets, as before described. By this means the machine is kept constantly at work, and no time is lost in clipping the stock by an independent mechanism and afterwards coiling the same on the reel to be fed properly to the machine. After the eyelet is completely formed, it is withdrawn from the die on the end of the punch *1*, to which it adheres, and is stripped off by the withdrawal of the punch into the former *2*, in the manner above explained, and it drops into a receptacle beneath the machine. It will, however, sometimes happen either that the eyelet will remain in the cavity of the die, or that it will adhere to the end of the punch, and if it is not removed by some special means, owing to the nature of the eyelet-forming instruments, will be the means of breaking or injuring the machine. To avoid the first-mentioned casualty with reference to the forming-die, I arrange at the rear of the die, as shown in fig. 5, a clearing-punch, *V*, which is thrust through the die from the rear after each eyelet is completed, and the punch *1* is withdrawn by means of the lever *T* and rod *R* operated by the cam *12*, on the main shaft, whereby the eyelet remaining in the die is surely removed before the operation of forming another eyelet in the die is commenced. The other casualty, which results from the eyelet sticking to the end of the punch, is avoided by means of the mechanism shown in figs. 6, 7, and 8, consisting of a delicate finger or clearer, *t*, that has a movement across the axis of the punch *1*, directly in front of the same, as indicated by the arrow, after the punch is drawn into the cutter, as described, in such a manner as to strike off the adhering eyelet from the punch. The clearer *t*, for this purpose, swings on the pivot *u*, by motion imparted to the lever *W* by the cam *X* on the main shaft and the action of the spring *g*, said spring carrying the clearer to the position shown in fig. 8, above the punch, and the positive movement of the cam *X* carrying the clearer across the axis of the punch in the direction indicated by the arrow, to strike off the eyelet in the manner shown and described.

Having thus described my invention, I wish it understood that I do not claim the compound moving and stationary instruments, by means of which the eyelet is formed from a metal strip, as described, the same having been previously patented by Jesse F. Richards, as above mentioned, and my said invention comprising only the improved construction of the said moving instruments as herein described, and the improved appliances described for aiding to carry into effect the general principle or mode of operation of the machine.

What I claim, and desire to secure by Letters Patent, is—

1. The improved mode of constructing and operating the compound male-cutter *3*, former *2*, and punch *1*, as described, for the purpose specified.
2. I claim a pair of reels, *C C'*, for holding and delivering and for taking up the metal strip, in combination with the eyelet-forming instruments for forming eyelets therefrom, substantially as described.
3. I claim a pair of sliding clamping-jaws, constructed and operating as described, in combination with suitable instruments for forming eyelets from a metal strip, as described, for the purpose specified.
4. I claim, in combination with the eyelet-forming instruments, constructed substantially as described, a

clipping or trimming mechanism for trimming off the perforated portion of the stock as it passes through the machine, substantially as described.

5. I claim the clearing-punch V, in combination with the compound female-cutter and forming-die, substantially as described, for the purpose specified.

6. I claim the clearer t, substantially as described, for the purpose specified.

In testimony whereof I have hereunto set my hand this third day of November, A. D. 1865.

SAMUEL W. ADAMS.
